(57) **CLAIM**

The ornamental design for a smartphone card wallet, as shown and described.

DESCRIPTION

FIG. 1 is an isometric view from the front of a smartphone card wallet incorporating the design in which dashed lines show stitching and are not hidden lines;

FIG. 2 is a front elevation view thereof;

FIG. 3 is a back elevation view thereof in which shading indicates an adhesive surface;

FIG. 4 is a left-side elevation view thereof;

FIG. 5 is a right-side elevation view thereof;

FIG. 6 is a top view thereof;

FIG. 7 is a bottom view thereof; and,

FIG. 8 is a plan view of the wallet when open.

The broken lines representing stitching are part of the claimed design.
